MUSICAL INSTRUMENT

J. Edward Legler, Fresno, Calif.

Application November 10, 1951, Serial No. 255,834

6 Claims. (Cl. 84—93)

The present invention relates to musical instruments and more particularly to an instrument which is economical to produce, is simple to play by even a novice and thus is suitable for use as a toy.

The development of musical appreciation in the very young has been inhibited by the lack of musical instruments of such simplicity of manipulation as to permit beginners promptly to achieve pleasing results. On certain simple instruments it has been possible for beginners to pick out simple melodies but the playing of appropriate harmony therewith has always required considerable skill. For example, many beginners find it not to difficult to play a simple melody on a harmonica but the complexities of appropriate tonguing precludes the achieving of desired harmony therewith by all except those who have developed a measure of proficiency. Many other instruments of the so-called toy class are difficult to master because of similar complexity of manipulation or prerequisite knowledge of scales or the like.

It is an object of the present invention to provide a musical instrument of increased simplicity of manipulation.

Another object is to provide a musical instrument of the character described that is attractive to children and sufficiently economical to produce to be suitable for sale as a toy.

Another object is to provide a musical instrument that permits even very young novices promptly to attain pleasing musical results.

Another object is to provide a musical instrument automatically providing visual indication of each musical note selected.

Another object is to provide a musical instrument in which the selection of successive notes in a melody automatically selects successively appropriate harmonic chords therefor.

Further objects and advantages will become apparent in the subsequent description in the specification.

Referring to the drawings:

Fig. 1 is a plan view of the musical instrument of the present invention having a portion thereof broken away to disclose certain internal construction.

Fig. 2 is a longitudinal section of the instrument taken along line 2—2 of Fig. 1.

Fig. 3 is a vertical transverse section through the instrument, as viewed from line 3—3 of Fig. 1.

Fig. 4 is a flattened illustration of a fragmentary portion of a cylindrical wall surface of a chamber in a housing of the present invention and a similarly flattened associated cylindrical valve sleeve utilized therein showing the relation of ports in said members.

Fig. 5 is a fragmentary transverse section similar to Fig. 3 but illustrating a second form of the invention in which two reed plates are employed rather than one reed plate as in the first form of the invention.

Fig. 6 is a view similar to Fig. 4 but of the second form of the invention.

Referring in greater detail to the drawings:

2

The musical instrument of the present invention is provided with an elongated generally cylindrical housing, indicated generally by the reference numeral 10, having a forward end 11 and a rearward or tail end 12. The 5 housing is conveniently molded to simulate the fuselage of an airplane and provided with a pair of wings 13 extending oppositely from a mid-portion of the housing, a pair of horizontally oppositely extending fins 14 and a vertically projecting rudder 15 adjacent to the tail end 12 simulating the empennage of an airplane. The upper side of the housing is bulged upwardly to simulate a cabin or cockpit cowling 16.

The housing 10 is of hollow construction being formed with a coaxial bore 20 at its tail end with the exterior surface of the tail end of the housing formed into a mouthpiece 21 so that air may conveniently be blown into the housing through the bore 20. A counterbore 22 of appreciably increased diameter is formed coaxially into the housing from its forward end for a substantial portion of its length forming a chamber 23 within the housing. A radially extending shoulder 24 is formed at the junction of the bore 20 and the counterbore 22 with the shoulder being recessed by a concentric annular groove 25 of the same diameter as the counterbore.

A tone producing structure 26 of elongated rectangular form, of a construction similar to the well known harmonica, is secured longitudinally against the underside of the housing and extends edgewards radially of the housing. The tone producing structure comprises a pair of elongated rectangular blocks 27 affixed to the housing in facing relation and having a plurality of grooves or passages 28 formed in their adjacent faces from their mid-portions to their edges adjacent to the housing. The tone producing structure 26 is also provided with a reed plate 29 of rectangular form having a plurality of reeds 30 equal in number to the number of passages in the blocks 27 attached at one of their ends across one of a plurality of reed openings 31 in a manner known in harmonicas. The lengths of the reeds are graduated for individual vibration periods so that the notes of a predetermined scale and extensions of the scale in octaves of said notes can be played thereby. The tone producing structure is assembled with the reed plate 29 secured between the blocks 27 with the rectangular passages 28 each in registry with a reed and reed opening in the reed plate. The assembled blocks and reed plate are formed with an arcuate surface at their mounting edge complementary to the housing which is glued, welded, soldered, or otherwise affixed to the housing 10.

Ports 33 are formed through the housing 10 radially of the chamber 23 individually in registration with the passages 28 in the manner illustrated in Fig. 4 in the drawing. Assuming that the notes of a musical scale are numbered from 1 to 8 and the octaves of the scale numbered upwardly above 8, the ports 33 are formed alternately to communicate with every other, or alternate passage 28 in the blocks 27. The ports 33 register with passages 28 at one side of the reed plate to sound the first, third, fifth, eighth and tenth notes of the predetermined scale. These notes are the notes of the tonic chord of the scale. The ports 33 are formed to register, at the opposite side of the reed plate 29, with passages 28 sounding the second, fourth, sixth, seventh and ninth notes of the predetermined scale. These notes when sounded together play the dominant ninth chord of the predetermined scale in a manner similar to the notes of a harmonica when air is drawn inwardly therethrough.

A somewhat streamlined guard is preferably positioned outwardly over each of the blocks 27 and in spaced relation thereto with an upper edge of each guard attached approximately tangentially to the outer surface of the housing 10 and a lower edge of each guard attached to the

outer surface of a respective block 27 adjacent to its lower edge. Each guard has a plurality of openings 37 formed therethrough for the emission of sound waves produced by the reeds 30.

A hollow cylindrical valve sleeve 40 is rotatably mounted in the chamber 23 in fitted engagement therewith. An end of the cylindrical valve sleeve rests in the recess 25 to preclude the passage of air from the interior to the exterior of the valve at its inner end. A plurality of sets of ports 41 are formed radially through the sleeve, as most clearly illustrated in Fig. 4 of the drawing. The ports 41 are formed in sets of three with each set adapted to register with predetermined ports 33 in the housing to sound three notes of the scale. The forwardmost opening in each set of openings is conveniently adapted to sound the desired melody note of a musical composition to be played thereby. The instrument is adapted to play ten notes of a scale, although this may be increased or decreased as desired, and octaves of the first and second notes indicated by the numerals 9 and 10.

For descriptive convenience the valve sleeve 40 is considered as being divided into ten longitudinal segments or divisions having sets of ports formed relative to these divisions to sound the desired notes. Referring to Fig. 4 of the drawings, a first set of three openings 41 shown at the top of the sleeve are formed in the first division of the sleeve so that when the sleeve is properly located these three openings are located over the openings 1, 3, and 5 above the reed plate. This conditions the instrument to sound the first melody note and the tonic harmony therewith. A second set of ports 41 are formed in the second division of the cylindrical valve 40 and are adapted to register with appropriate ports 33 when properly positioned to sound the second, fourth, and sixth notes of the scale, the second note being the melody note, the fourth and sixth supplying the proper seventh harmonic for the second note. Other sets of ports 41 are located in their respective divisions of the sleeve to form all notes of the octave, extension notes and predetermined harmonic chords. All melody notes are shown to have two accompanying notes thereabove in harmony therewith except the extension notes numbered 9 and 10. By increase of the number of reeds 30 and passages 29 and appropriate valve sleeve modification any desired musical range can be attained.

The cylindrical valve sleeve 40 is manually rotatable to position selected ports 41 in registry with their companion ports 33 by mounting a plug 44 of cylindrical form rigidly in the forward end of the sleeve. Forwardly of the forward end of the cylindrical valve, the plug 44 is axially extended in reduced diameter, as at 45. In order to maintain the cylindrical valve 40 endwardly in the housing 10, a collar 47 is provided having a coaxial bore 48 and a counterbore 49 defining a shoulder 50 therebetween. The forward end of the housing 10 is formed with a cylindrical nipple 51. The counterbore 49 of the collar 47 is fitted over the nipple 51 and glued or otherwise affixed thereto with the shoulder 50 in abutting relation to the forward end of the valve sleeve 40. The plug 44 is rotatably extended through the bore 48 and mounts a circular disc 54 concentrically thereon in simulation of a whirling propeller. A plurality of numbers 55 are etched, stamped, printed, or otherwise shown on the rearward face of the disk adjacent to the periphery thereof and in substantially equally spaced relation thereabout. The numbers 55 correspond to the divisions of the valve sleeve 40 shown in Fig. 4 and are so positioned that when aligned with a pointer 56 attached on the cockpit cowling 76, ports 37 of their respective division are aligned with the predetermined ports 33 to precondition the instrument to play a chord. For convenience in positioning the valve sleeve 40, a knurled knob 60 is preferably provided on the forwardly extended end of the plug 44. It will be apparent that a person blowing through the mouthpiece 21 can by visual

reference to the pointer 56 and numerals 55 select successive chords to achieve a desired musical expression.

It will be apparent that any suitable material may be utilized in the molding, fabrication or other formation of the instrument of the present invention but the applicant prefers to utilize plastic or hard rubber for the housing 10, wings 13, empennage 14-15, sleeve 40, disk 54, knob 60, blocks 27, reed plate 29, and chords 36. Metal is generally preferred for the reeds 30 but not essential to the successful operation thereof.

Second form

A second form of the invention is illustrated in Figs. 5 and 6, incorporating a modified tone producing structure 66. This tone producing structure is provided with a single block 67 of rectangular form having a plurality of passages 68 formed in opposite sides faces thereof from a mid-portion to one edge thereof. A pair of reed plates 69 are provided, each having a plurality of reeds 70 mounted thereon with one of the reed plates attached to each side face of the block 67. The reed plates and block are attached edgewards to the housing in a manner similar to the first form of the invention with guards 71 mounted outwardly in spaced relation to the reed plate so that the reeds are protected.

In a manner somewhat similar to the first form of the invention, ports 76 are formed through the housing 10 registering with all of the passages 68. Sets of ports 77 are formed through a cylindrical valve sleeve 78, similar to the sleeve 40 in sets adapted to play predetermined melody notes and accompanying chords. The valve sleeve is divided into ten divisions with the sets of ports located in predetermined positions.

Referring to Fig. 6, it will be apparent that in one position of the valve sleeve 78, the first set of ports 77 are positioned to sound the first, third, and fifth notes of the scale. When the sleeve 78 is rotated to bring the first set of ports over the other passages 68, the second, fourth, and sixth notes are sounded, and so on.

Operation

The operation and utility of the present invention are believed to be clearly apparent and are briefly summarized at this point. In playing the musical instrument of the present invention, a player blows into the mouthpiece. The numerals 66 on the disk 54 provide a visual aid to chord selection. For example, the number "1" on the scale 55 identifies the tonic chord, "2" the supertonic, "3" the mediant, "4" the subdominant, "5" the dominant, "6" the submediant, "7" the leading tone, "8" the octave of the tonic, "9" the octave of the second or supertonic, and "10" the octave of the third or mediant. The player may, by rotation of the knob 60, play many musical compositions that have their melody notes as notes of the tonic scale with automatically accompanying tonic or dominant harmony. A sheet or booklet may accompany the musical instrument indicating the melody notes of musical compositions by the number of notes in the scale. Thus, by reading the numbers, the player may easily, without previous instruction, play many musical compositions with pleasing results.

Although the invention has been herein shown and described in what are conceived to be the most practical and preferred embodiments, it is recognized that departures may be made therefrom within the scope of the invention, which is not to be limited to the details disclosed herein but is to be accorded the full scope of the claims so as to embrace any and all equivalent devices and structures.

Having described my invention, what I claim as new and desire to secure by Letters Patent is:

1. A toy musical instrument comprising an elongated housing simulating the appearance of the fuselage of an airplane having a forward and a rearward end portion, said housing having an elongated cylindrical chamber

formed axially longitudinally therein, a bore concentric to the chamber and of a reduced diameter formed through the forward end of the housing into the chamber, a bore concentric to the chamber and of a reduced diameter formed through the rearward end of the housing into the chamber, and a plurality of ports formed through the housing radially of the chamber in alignment longitudinally of the housing; simulated airplane wings laterally extended from the housing; a simulated airplane empennage mounted adjacent to the rearward end portion of the housing; a hollow cylindrical valve sleeve rotatably mounted in the chamber having ports formed radially therethrough selectively registerable with the ports in the housing in response to rotational positioning of the sleeve; sounding reeds borne by the housing in alignment with the ports therein; a plug rigidly mounted in the forward end of the valve sleeve and rotatably extended through the forward bore of the housing; and a circular disk mounted concentrically on the plug exteriorly of the housing having valve sleeve position indices thereon.

2. A toy musical instrument comprising an elongated housing simulating the appearance of the fuselage of an airplane having a forward and a rearward end portion, said housing being formed with a cylindrical bore extended longitudinally inwardly of the housing from the rearward end thereof and a counterbore coaxially aligned with the bore extended longitudinally of the housing inwardly from the forward end thereof, and a plurality of ports formed through the housing radially of the counterbore in alignment longitudinally of the housing; simulated airplane wings laterally extended from the housing; a simulated empennage adjacent to the rearward end of the housing; a cylindrical valve sleeve rotatably mounted in the counterbore having peripheral ports successively registerable with the ports in the housing upon sleeve rotation; vibratory sound producing means mounted on the housing for engagement by air directed through the ports of the housing; a plug rigidly mounted in the forward end of the sleeve having a cylindrical portion forwardly extended from the housing; a cap mounted on the forward end of the housing having the plug extension journaled therein; and a circular disk rigidly mounted concentrically on the plug extension having visual indices thereon disposed toward the forward end portion of the housing positioned in corresponding relation to the peripheral ports at the valve sleeve.

3. A toy musical instrument comprising an elongated housing having a bore longitudinally thereof from one end of the housing and a counterbore longitudinally of the housing from the opposite end thereof, the bore and the counterbore being substantially coaxially aligned and intersecting, the end of the housing having the bore being in the form of a mouthpiece, and the housing having a plurality of ports radially extended from the counterbore to the exterior of the housing in substantial alignment longitudinally of the housing; a block mounted on the housing having a plurality of air passages therethrough aligned with the ports of the housing; vibratory sound means mounted in the air passages of the block; a hollow cylindrical valve sleeve rotatably mounted in the counterbore of the housing having sets of ports in the periphery thereof registerable with the ports in the housing; a plug fixedly mounted in the end of the valve sleeve opposite to the mouthpiece a cylindrical portion in sealing relation in the sleeve and having a concentric axial extension of reduced diameter extended from the housing, the plug having an axially disposed shoulder between the cylindrical portion and the extension; a cap mounted on the end of the housing opposite to the mouthpiece in closing relation to the counterbore with the plug extension rotatably extended therethrough and in engagement with the shoulder of the plug holding the plug and sleeve within the counterbore; and a note indicating disk mounted concentrically on the plug extension externally adjacent to the cap for unitary rotational movement with the plug and

valve sleeve having visual indices thereon disposed toward the mouthpiece individually positioned on the disk in corresponding relation to the positions of the individual sets of ports in the valve sleeve.

- 5 4. A musical instrument comprising a hollow elongated housing open at its forward end, said open end constituting a mouthpiece for the instrument, a section of the housing adjacent the rearward end of the housing having the hollow thereof in the form of a cylindrical chamber of circular cross-section, a hollow cylindrical valve sleeve of circular cross-section coaxial with and in the chamber, the outer diameter of the valve sleeve being substantially equal to that of the chamber whereby the sleeve is rotatable in the chamber, said sleeve being open at its forward end and closed at its opposite end whereby the sleeve will receive air blown into the mouthpiece, the housing having a plurality of ports through the walls of the chamber forming section, the sleeve having a plurality of ports through the cylindrical wall of the sleeve, said sleeve ports being selectively registerable with the chamber ports by rotation of the sleeve in the chamber to form air passageways extending from the hollow of the sleeve to externally of the housing, air actuated sound-emitting means, means mounting the sound-emitting means on the housing in association with the ports for actuation thereof by air passing through said passageways, means fixed to the sleeve and extending rearwardly and externally of the housing for effecting rotation of the sleeve in the chamber, port registration indicating means fixed on the external end of said means for effecting rotation of the sleeve, said indicator means extending beyond the external surface of the rearward end of the housing, and indicator means on the external surface of the housing, whereby when said indicating and indicator means are selectively aligned, at least one of the sleeve ports will be in registry with one of the chamber ports to form one of said air passageways.
- 10 5. A musical instrument comprising a housing having a bore extending from a forward end to a rearward end of the housing, the bore opening at the forward end of the housing to provide a mouthpiece opening for the instrument, a counterbore coaxial with and of larger diameter than the first mentioned bore and extending inwardly of the housing from said rearward end, the counterbore being cylindrical and of circular cross-section to define a valve chamber, a hollow cylindrical valve sleeve of circular cross-section within the chamber and of an axial length substantially equal to that of the counterbore, the outer diameter of the sleeve being substantially equal to the counterbore whereby the sleeve is rotatable in the chamber, means on the rearward end of the housing for maintaining the sleeve in the chamber, the sleeve being open at that end thereof nearer the mouthpiece opening and closed at its opposite end, the housing having a plurality of ports extending through the walls defining the chamber, the sleeve having a plurality of ports through the cylindrical wall of the sleeve, the sleeve ports being selectively registerable with the chamber ports by rotation of the sleeve in the chamber to selectively form air passageways extending from the hollow of the sleeve to externally of the housing, a plurality of air actuated sound-emitting means mounted on the housing individually adjacent to the ports and actuated by air passing through the passageways, an axially directed stem fixed on said opposite end of the sleeve and extending beyond the rearward end of the housing for effecting rotation of the sleeve in the chamber, a circular disk fixed on and coaxial with the stem and positioned rearwardly of the rearward end of the housing, said disk being of larger diameter than the periphery of the rearward end of the housing to provide a peripheral portion on the inside face of the disk which is visible from the mouthpiece end of the instrument, indicia spaced about said peripheral portion, and a pointer on the exterior of the housing whereby the indicia are selectively alignable with the pointer to selectively align the sleeve and the chamber ports.
- 15 20 25 30 35 40 45 50 55 60 65 70 75

6. A musical instrument comprising a housing having a bore extending from a forward end to a rearward end of the housing, the bore opening at the forward end of the housing to provide a mouthpiece opening for the instrument, a counterbore coaxial with and of larger diameter than the first mentioned bore and extending inwardly of the housing from said rearward end, the counterbore being cylindrical and of circular cross-section to define a valve chamber, a hollow cylindrical valve sleeve of circular cross-section within the chamber and of an axial length substantially equal to that of the counterbore, the outer diameter of the sleeve being substantially equal to the counterbore whereby the sleeve is rotatable in the chamber, means on the rearward end of the housing for maintaining the sleeve in the chamber, the sleeve being open at that end thereof nearer the mouthpiece opening and closed at its opposite end, an axially directed row of spaced apart and radially extending ports through the walls defining the chamber, a plurality of circumferentially spaced apart axially directed rows of radially extending ports through the cylinder wall of the sleeve, each of the sleeve ports being selectively registerable with a chamber port to form an air passageway extending from the hollow of the sleeve to externally of the housing, air actuated sound-emitting reeds mounted on the housing and associated one with each of the chamber ports for actuation by air passing through their respective chamber ports, an axially directed stem fixed to the closed end

5
10
15
